UNITED STATES PATENT OFFICE.

HENRY B. BEACH AND HENRY KAYSER, OF MERIDEN, CONNECTICUT,
ASSIGNORS TO THE INTERNATIONAL SILVER COMPANY, OF MERIDEN,
CONNECTICUT, A CORPORATION OF NEW JERSEY.

DESIGN FOR A BACK FOR HAND-MIRRORS, BRUSHES, AND SIMILAR ARTICLES.

No. 38,066.

Specification for Design.

Patented June 12, 1906.

Application filed April 27, 1906. Serial No. 314,101. Term of patent 3½ years.

To all whom it may concern:

Be it known that we, HENRY B. BEACH and HENRY KAYSER, citizens of the United States, residing in the city of Meriden, New Haven county, and State of Connecticut, have invented a new, original, and ornamental Design for the Backs of Hand-Mirrors, Brushes, and Similar Articles, the same being disclosed in the accompanying drawings, in which the view is a back elevation.

We claim—

The ornamental design for a back for hand-mirrors, brushes, and similar articles, as shown.

HENRY B. BEACH.
HENRY KAYSER.
